WASHING MACHINE

Sidney S. Holland, Sandusky, Ohio, assignor, by
mesne assignments, to The Apex Electrical
Manufacturing Company, Cleveland, Ohio, a
corporation of Ohio

Application February 27, 1936, Serial No. 66,047

13 Claims. (Cl. 68—54)

My invention relates to washing machines of dolly type, and has for its principal object to provide a dolly constructed and adapted for operation whereby dirt may be removed from clothing, fabrics, or the like, that are contained in the tub of the machine along with wash water, by combined beating, rubbing and flushing actions resulting from reciprocation of the dolly.

Dirt tending to soil clothing or other articles of fabric, whether consisting of fine, solid particles, or greasy substances, becomes lodged, not only in the interstices between threads of the fabric, but also in and between fibers of the individual threads, to which it adheres with such tenacity as to resist dislodgment merely by flushing with water. The threads and fibers of the fabrics must, therefore, be distorted to dislodge or loosen the dirt particles from the threads and fibers so that the particles can dissolve, precipitate in the water, or be floated off with soap.

While modern washing machines effect dislodgment and removal of dirt from fabrics more quickly and conveniently than was possible with older and cruder methods, such as pounding the fabrics while wet between flat surfaces, rubbing the fabric while wet over corrugated surfaces, tumbling or pushing the fabric back and forth in a tub of water and simultaneously flushing water through the fabric, as with machines of reciprocating cylinder, peg dolly or agitator type, or pulling the dirt from the fabric as with machines of the vacuum beater type, the principle of flushing away the dirt after its dislodgment by distortion of the threads and fibers of the fabric is the same today as it always has been.

My invention involves the same principles; the advantage claimed for it being that with a dolly embodying my improvements, both beating and rubbing of the fabrics and flushing of dirt therefrom may be accomplished either simultaneously or in rapid sequence to effect the desired cleansing more simply, quickly and efficiently than with devices heretofore known or used for the same purpose.

A preferred form of washing machine embodying my invention is illustrated in the accompanying drawings, wherein:

Fig. 1 is a perspective view of a washing machine including a dolly embodying my invention, a part of the tub of the machine being broken away to illustrate the dolly submerged in wash water.

Fig. 2 is a vertical section on the line 2—2, Fig. 5, particularly illustrating the tub, the dolly,

and means for mounting and operating the dolly in the tub.

Fig. 3 is a similar view on the line 3—3, Fig. 5.

Fig. 4 is a detail perspective view of the dolly and its mounting barrel, looking upwardly into the dolly.

Fig. 5 is a horizontal section of the tub and plan view of the dolly.

Fig. 6 is a horizontal section of the dolly mounting and actuating shaft on the line 6—6, Fig. 2.

Fig. 7 is an enlarged, central, vertical section of the upper end of the dolly spindle and barrel, particularly illustrating the clutch for operatively connecting the spindle with the barrel.

Fig. 8 is an enlarged, detail, perspective view of the clutch plug member of the barrel, and a part of the clutch socket member of the spindle.

Fig. 9 is an enlarged section through the dolly, spindle barrel and clutch plug, on the line 9—9, Fig. 7.

Fig. 10 is a perspective view of the lower portion of the machine tub, parts being broken away to show the motor and its driving connections with the dolly shaft.

Referring more in detail to the drawings:

1 designates a tub, here shown to be of double wall construction and circular in cross-section, including an inner member 2 having a rounded lower edge 3, a flat bottom 4 having a slightly raised central section 5, and an upper edge 6 provided with an inwardly directed bead 7 forming a seat 8 for a removable cover 9 and a bend 10 forming a lap joint with the outer tub member 11.

The tub members 2 and 1 are preferably of different diameter to provide space between their side walls for insulating material 12, and the outer member 11 has a skirt portion 13 extending below the bottom of the inner member for support on legs 14 that are attached thereto by fastening devices 15. The skirt forms a chamber for housing the motor 16, its shaft 17, gearing indicated at 18 for actuating the wringer drive shaft 19, a crank 20 driven by the gearing, and a pitman 21 operatively connecting the crank with an arm 22 keyed through a link mechanism 23. The arm 22 is secured on a shaft 24 journalled in suitable bearings and extending vertically into the inner tub member at the center thereof for reciprocating a dolly.

Surrounding the shaft 24, within and at the center of the tub 2, is a tapered, tubular spindle 25 having an enlarged base 26 seated on the raised portion 5 of the tub bottom 4 and having a neck 27 extending through an aperture 28 in said raised portion into threaded engagement with a collar 29.

29 on a casting 30, located beneath the tub. The casting 30 includes a plate 31 spaced beneath the bottom of the tub to which the inner ends of brace arms 32 are secured. The brace arms 32 extend radially from the plate to the legs 14 and assist in supporting the tub, as well as provide supports for the motor and the transmission mechanism connected therewith. Gaskets 33 and 34 are interposed between the base of the spindle 25 and the bottom of the tub, and between the bottom of the tub and the suspended casting 30 at the time of assembling the parts.

Formed in the upper portion of the spindle 25 is a chamber 35 seating a bearing 36 for the upper end of the dolly shaft 24. Seated on the spindle 25, and closing the top of the chamber 35 and the annular space 37 between the housing and the dolly barrel presently described, is a disk 38, and overlying the disk is a washer 39. Located above the disk and washer, and keyed to the shaft 24 by a pin 41 or the like, is a clutch member 42, circular in cross-section to provide a bearing for the dolly barrel, later described. The clutch member 42 has a rectangular socket 43 extending diametrically over the top of the shaft and opening through the outer end thereof.

The lower end of the spindle 25 is stepped to form the bottom bearing flange 44 of substantial area for stabilizing mounting of the spindle on the bottom of the tub and seats 45 and 46 for supporting the bearing rings 47 and 48.

The construction above described is all in accordance with common practice and is illustrated to disclose a washer with which my invention is associated, as now to be described.

The dolly, indicated generally at 49, includes a body member 50 preferably of heavy sheet or light cast metal and of frustro-pyramidal shape, the side walls 51 of the body being progressively stepped from their larger dimensions at the bottom to their smaller dimensions at the top to provide a succession of rubbing surfaces 52 resembling the ribs of an ordinary washboard, but even more sharply defined because of the angular meeting of the shelf and riser portions 53-54 of the stepped walls 51, the shelf and riser portions being arranged substantially tangential to arcs of oscillation about the axis of the dolly. The body 50 is preferably four-sided and constructed of a single piece, or the meeting edges of adjacent sides may be welded or otherwise sealed to make the body water-tight, and the upper edges of the side members are likewise sealed to a top closure plate 55.

Extending centrally through the body from a point slightly above the bottom plate thereof, and through the top plate 55 to a height slightly below the top of the tub when the parts are assembled, is a tapered barrel 56 of a diameter at its lower end to seat on a supporting ring 48 at the base of the spindle 25 and having an annular recess 57, seating bearing ring 58 engaging bearing ring 47.

The upper end of the barrel 56 is reduced in diameter to form a dome 59 having a socket 60, circular in cross-section and dimensioned to receive and form a bearing for the clutch member 42 on the dolly shaft. The top of the dome has a rectangular opening 61 therethrough, adapted to register substantially with the socket 43 in the clutch member 42. Mounted for longitudinal sliding movement on the dome 59 is a cap 62 having a side wall encircling the outer face of the dome.

55 Suspended from the cap 62, by a pin 63 or the

like, for slidable travel in the opening 61 in response to movement of the cap over the dome, is a clutch plug 64 adapted for projection into the socket 43 when the slots in the clutch member and cap are in registration to operatively connect the dolly shaft and barrel for oscillation of the dolly in response to corresponding movement of the shaft. 65 designates a groove in one of the side faces of the clutch plug 64, and 66 a ball movable in a channel 67 in the side of the dome 10 and urged to contact with the base of said groove by a spring 68 held in the channel by a plug 69. The ball and spring thus serve as a latch to yieldingly hold the clutch plug in adjusted position.

Attention is directed to the fact that the distances across the corners 70 at the base of the dolly are such that they move in close proximity to the rounded bottom edge of the tub, as shown in Figs. 3 and 5.

Vent holes 71 and 72 are provided in the plate 20 55 and the barrel 56 respectively, for preventing any air pressures or vacuums being formed which would affect easy insertion or renewal of the dolly from the tub.

Assuming the tub and operating parts of the 25 machine to be constructed and assembled as described, the dolly is inserted into the tub with its barrel fitted over the stationary central housing in limited frictional contact therewith at the upper and lower bearing points, and with the 30 bottom of the dolly in such close proximity to the bottom of the tub as to prevent articles being washed from passing beneath the lower edge of the dolly, while allowing ample clearance to avoid interference with oscillation of the dolly. 35

The driving parts of the machine are started in operation by turning the motor switch to rotate the wringer drive shaft and oscillate the dolly shaft through the pitman 21 and crank arm 22.

Further assuming that a sufficient quantity of 40 water for washing a determined quantity of clothes or other articles has been deposited in the tub, the dolly is started in operation by projection of the clutch plug 64 on the cap 62 into the socket 43 in the clutch member 42 on the shaft 24. 45 The dolly, thus clutched to the shaft, will oscillate therewith, setting up currents in the water in response to centrifugal force generated by limited rotary movement of those portions of the dolly of greater radius, first in one direction and then in the other, and deflection of the currents from the side of the tub; that part of each of the risers of each side wall of the pyramidal body between its longitudinal center and one of its ends serving as a blade to force the water outwardly and laterally when the dolly is moved in one direction, and the portion of the riser between such center point and its opposite end likewise serving to force the water outwardly and laterally in the opposite direction when travel of 50 the dolly is reversed. 55

The greatest force of the currents thus set up occur at the bottom of the tub where the risers are of greatest length, the forces of the currents gradually diminishing as the lengths of the risers 65 decrease toward the top of the body, the currents taking a course outwardly from the center points and along the wall of the tub to convergence, thence upwardly along the wall of the tub, inwardly to the dolly and down the wall of the 70 dolly to rejoin the upward flow on approximately the line of the arrows, Fig. 1, a slight suction being created adjacent the wall of the dolly along said center lines that aids in direction and maintenance of the currents. Oscillation of the dolly 75

tends to move the water circumferentially as well as radially, thus causing currents set up by opposite ends of the blade-like portions of the side walls of the dolly to meet tangentially and proceed together in rolling, unified flow.

5 After the dolly has been placed in operation the articles of clothing or fabrics to be cleansed are dropped into the wash water and picked up by the currents to circulate therewith, the circulating and rolling forces of the currents being sufficient to tumble the articles about as they are carried along in the current, so that different portions and both faces of the fabrics are successively presented to the risers for impact thereby and to distort the threads and fibers of the fabrics and flush water through the fabric just as such effect is produced by beating with other types of washing apparatus, and the articles carried downwardly over the steps or ribs of the 10 dolly to distort the threads and fibers by a rubbing contact with the edges of the stepped portions of the side walls of the dolly just as such effect is produced by rubbing of clothing or pieces of fabric against an ordinary washboard.

15 20 25 It is apparent, therefore, that with a dolly constructed and operated according to my invention I am able to secure the combined advantages of beating, rubbing and flushing effected with washing machines and devices heretofore in separate use, but by a single operation.

30 35 40 It has been determined from experience that when operating to capacity, a machine of this general type will work satisfactorily with a load of about eight pounds of articles to be cleansed, but that regardless of the load a full charge of water is usually required. With a dolly of my improved construction I can, however, proportion the water to the amount of the load without impairing the washing operation, thus effecting a saving in water and soap, as well as a saving of labor in supplying and disposing of the surplus water.

What I claim and desire to secure by Letters Patent is:

45 1. A washing machine including a tub, means for supporting a dolly in the tub, a dolly supported by said means for oscillation on an axis substantially perpendicular to the bottom of the tub and including a downwardly and outwardly inclined side wall sloping in a radial direction from said axis and having a series of transverse rubbing surfaces on its outer face, and means for oscillating the dolly.

50 55 60 65 70 2. A washing machine including a tub, means for supporting a dolly in the tub, a dolly supported by said means for oscillation on an axis substantially perpendicular to the bottom of the tub and including a downwardly and outwardly inclined side wall sloping in a radial direction from said axis and having vertically spaced, horizontal rubbing surfaces on its outer face, and means for oscillating the dolly.

75 80 85 90 95 3. A washing machine including a tub, means for supporting a dolly in the tub, a dolly supported by said means for oscillation on an axis substantially perpendicular to the bottom of the tub and including a downwardly and outwardly inclined side wall sloping in a radial direction from said axis and having vertically spaced, transverse rubbing surfaces on its outer face, and means for oscillating the dolly.

4. A washing machine including a tub, means for supporting a dolly in the tub, a dolly supported by said means for oscillation on an axis substantially perpendicular to the bottom of the

tub and including a frustro member having a noncircular perimeter to form a downwardly and outwardly flared side wall having spaced, horizontal rubbing surfaces on its outer face increasing in width from the top to the bottom of the 5 dolly, and means for oscillating the dolly.

5. A washing machine including a tub, means for supporting a dolly in the tub, a dolly supported by said means for oscillation on an axis substantially perpendicular to the bottom of the 10 tub and including a frustro pyramidal body forming a plurality of side walls each disposed angularly relative to an adjacent wall and having spaced transverse protuberances on its outer face adapted for scrubbing contact by articles of 15 fabric circulating downwardly with wash water along the sides of the dolly, and means for oscillating the dolly.

6. A washing machine including a tub, means for supporting a dolly in the tub, a dolly supported by said means for oscillation on an axis substantially perpendicular to the bottom of the tub and including a frustro pyramidal body forming a plurality of side walls each disposed angularly relative to an adjacent wall and provided 20 with alternate, transverse, vertical, beating portions and horizontal rubbing portions, and means 25 for oscillating the dolly.

7. A washing machine including a tub, means for supporting a dolly in the tub, a dolly supported by said means for oscillation on an axis substantially perpendicular to the bottom of the tub and including a plurality of downwardly and outwardly flared side walls each disposed angularly relative to an adjacent wall, and provided 30 with alternate, transverse, vertical, beating portions and horizontal rubbing portions arranged 35 substantially tangential to arcs of oscillation about said axis, and means for oscillating the dolly.

8. A washing machine including a tub, means for supporting a dolly in the tub, a dolly supported by said means for oscillation on an axis substantially perpendicular to the bottom of the tub and including a side wall stepped to provide 40 alternate risers arranged substantially tangential to arcs of oscillation about said axis and adapted for creating circulatory currents of wash water radially within the tub and for beating 45 contact with articles of fabric conducted by said currents downwardly along said side wall in response to oscillation of said dolly and rubbing surfaces adapted for contact with said articles during said downward travel thereof, and means 50 for oscillating the dolly.

9. A washing machine including a tub, means for supporting a dolly in the tub, a dolly supported by said means for oscillation on an axis substantially perpendicular to the bottom of the tub and including a side wall having riser portions substantially perpendicular to the bottom of the tub adapted for creating circulatory currents of wash water in the tub in response to oscillation of the dolly and for beating articles of fabric flowing downwardly in said currents 60 along the side of the dolly, step portions substantially horizontal with the bottom of the tub and edge portions connecting the riser and step portions adapted for rubbing contact by said articles of fabric during said downward flow, said riser 65 and connecting edge portions being arranged in planes tangential to arcs of oscillation about said axis and means for oscillating the dolly.

10. A washing machine including a tub, means for supporting a dolly in the tub, a dolly sup- 75

- ported by said means for oscillation on an axis substantially perpendicular to the bottom of the tub and including a downwardly flared side wall having riser portions substantially perpendicular to the bottom of the tub adapted for creating circulatory currents of wash water in the tub in response to oscillation of the dolly and for beating articles of fabric flowing downwardly in said currents along the side of the dolly, step portions substantially horizontal with the bottom of the tub and edge portions connecting the riser and step portions adapted for rubbing contact by said articles of fabric during said downward flow, and means for oscillating the dolly.
11. A washing machine including a tub, a spindle supported in said tub, a dolly including a barrel oscillatably mounted on said spindle, and a plurality of downwardly and outwardly flared side walls having stepped outer faces forming alternate vertical beating and horizontal rubbing surfaces, a shaft extending through said spindle, means for oscillating the shaft, and means for selectively connecting the dolly with the shaft.

12. A washing machine including a tub, a dolly of substantially frustro pyramidal shape to form faces sloping outwardly and downwardly and increasing in width from the apex toward the base of the dolly, means supporting the dolly within the tub for oscillation about its axis, means for oscillating the dolly, and a plurality of protuberances on said faces adapted for rubbing contact by articles of fabric circulating downwardly with wash water over the faces of the dolly.

13. A washing machine including a tub, a dolly of substantially frustro pyramidal shape to form faces sloping outwardly and downwardly and increasing in width from the apex toward the base of the dolly, means supporting the dolly within the tub for oscillation about its axis, means for oscillating the dolly, and a plurality of progressively stepped rib-like portions to form shelf and riser portions extending transversely across the width of said faces for contact by articles of fabric circulating downwardly with wash water over the faces of the dolly.

SIDNEY S. HOLLAND.
